CRATE FOR WATER BOTTLES OR CARBOYS

Carl Eugene Johnson, Lomita, Calif.

Application July 4, 1939, Serial No. 282,796

1 Claim. (Cl. 217—54)

This invention relates to a crate for holding large glass bottles or carboys, whereby the same may be transported and stored with a minimum risk of breakage.

Heretofore, the crates employed for handling large glass bottles have been constructed principally of wood, and the cost of repairing such crates constitutes an important factor in the sale and distribution of spring and distilled water. The present invention has for its principal object the production of a novel and efficient crate for large glass bottles or carboys which is constructed of metal and so designed as to withstand the transportation and storage of large glass bottles to the end that the cost normally incident to such business of repairing the crates will be materially reduced.

In the crate of the present invention, the carboy or bottle is supported on metallic bars of spring character which act as sockets or receptacles for the lower end of the bottle and maintain the same properly spaced from the side of the crate. The crate of the present invention is constructed out of suitable shock-proof steel in a skeleton manner. The frame of the crate is light-weight, strong and durable in its construction and also arranged so that the packing and removal of the carboy or bottle is readily effected.

Various novel features of the present invention, together with further objects and advantages thereof, will be fully understood from a description of the preferred form or example of a crate embodying the present invention. For this purpose, one practical embodiment of the present invention is illustrated in the accompanying drawing.

In the drawing:

Figure 1 is an elevation of the crate showing in dotted lines a bottle or carboy in position therein.

Figure 2 is a plan view.

Figure 3 is a vertical section on the line 3—3 of Figure 2.

Figure 4 is a fragmentary plan of a modified form of crate.

Figure 5 is a fragmentary vertical section on the line 5—5 of Figure 4.

Referring to the drawing, the crate comprises an outer frame formed by a base plate 2, which is provided with a rectangular opening 3 in the center thereof and which has four turned up and beaded portions 4 to act as horizontal braces. The four horizontal bracing portions 4 of the base are arranged in the form of a square, but are provided with spaces between the same for the

reception of vertical posts 5. The vertical posts 5, as well as the base 2 of the frame, are formed of sheet or plate shock-proof metal. The posts 5 are bent into substantially V-shape in cross section and are provided with one or more beads 6 in each of the legs of the V. for stiffening the posts. At the upper end of the posts 5 there are provided horizontal braces 7 interconnecting the posts, four of the braces 7 being provided to form a complete frame. Said braces are likewise formed of shock-proof metal of sheet or plate form bent to provide beads 8 for stiffening the same. By constructing the frame of the crate with the bottom posts and the horizontal braces 15 of such plate from shock-proof metal a light-weight and inexpensive frame for the crate is provided which is of sufficient rigidity and strength to stand the wear of handling and transporting carboys of large water bottles without material deterioration and use.

For properly mounting the carboy or bottle within the frame thus formed there is provided a pair of bars 9 and 10, which are composed of spring metal and extend diagonally across 25 the crate. Such spring bars are each rigidly attached to the vertical posts 5, as indicated at 5^a, by means of bolts, rivets, or welding, and from their ends they are bent in the form of loops 11 and hence downwardly where the loops 30 join flat portions 12 of the bars, which flat portions 12 are designed to form a seat for a bottle or carboy supported in the crate. The inner portions of the loops 11 act to form vertical guides for the lower end of the bottle or carboy for guiding the same against the seat portions 12 of the bars. By this means, the bottle or carboy is suspended by the bars 8 above the base 2 of the frame and likewise spaced from the sidewalls of said frame. The support thus 35 provided is of a resilient flexible nature adapted to withstand shocks incident to handling and transporting bottles or carboys. Preferably, packing material is associated with the spring bars for preventing or limiting contact between 40 the glass bottles or carboys and the suspension bars, and a preferred form of such packing is indicated as consisting of a rope 13 woven in openings 14 on the bars so as to be interposed particularly at the corners of the bottles between the bottles and suspension bars.

For holding the upper portion of the bottle from excessive movement, I provide corner bars 7^a welded to the horizontal braces 7 around which is placed suitable buffering material 15. As indicated in Figures 4 and 5 alternatively, the

corner bars 14^a may support wood spacers 16, as by links 17, fitting in grooves in the corner bars 14^a.

As indicated, the frame of the crate may have its component parts, i. e., the base, posts, and horizontal braces 7 welded together or connected in any other suitable or preferred manner.

While the particular form of crate for carboy or other large bottle herein described is well adapted to carry out the objects of the present invention, it is to be understood that various changes and modifications may be made without departing from the principles of the present invention, and the present invention includes all such changes and modifications as

come within the scope of the following claim.

I claim:

A crate for a carboy or water bottle, comprising a frame formed of sheet metal and including a base plate having upturned and beaded portions, said frame also including V-shaped post sections beaded vertically and united to the said upturned portions, the upper portions of said post sections being connected by horizontally extending members, and spring suspension means including members attached to the lower portions of said corner posts and curved hence upwardly into the form of a vertical loop located in the lower portion of the frame and extending hence inwardly to form a seat.

CARL EUGENE JOHNSON.
